P. O. WISWELL

VALVE SPRING LIFTER

Filed Jan. 6, 1927

INVENTOR.
Perry Otis Wiswell,
BY

Geo. P. Kimmel ATTORNEY.

UNITED STATES PATENT OFFICE.

PERRY OTIS WISWELL, OF WACO, TEXAS.

VALVE-SPRING LIFTER.

Application filed January 6, 1927. Serial No. 159,393.

The invention relates to a valve tool for use in connection with internal combustion engines, and more particularly to the class of valve spring lifters.

5 The primary object of the invention is the provision of a tool of this character, wherein the construction thereof enables its adjustment so as to accommodate various sizes of valves and their springs within an internal combustion engine, so that the spring for each valve can be lifted, to permit the withdrawal of the valve with dispatch and in a ready manner.

Another object of the invention is the provision of a tool of this character, wherein it is readily adjustable, so that the same can be applied to the valve and the support for the spring of said valve and may be locked to sustain the valve spring compressed, to 20 permit the freeing of the valve when mounted within the internal combustion engine.

Another object of the invention is the provision of a tool of this character, wherein the construction thereof is novel in form, so 25 as to render the same readily adaptable for varying styles of valves, springs and supports therefor.

A still further object of the invention is the provision of a tool of this character, 30 wherein the gripping elements or members thereof are readily and easily adjusted to engage the parts, that is the valve head whether it be perforated or slotted and the spring seat, so that the valve can be freed 35 when within the internal combustion engine, without excessive labor on the part of the operator or user of the tool.

A still further object of the invention is the provision of a tool of this character, 40 which is extremely simple in construction, possessing but few parts, these being readily adjustable, thoroughly reliable and efficient in its purpose, strong, durable, and inexpensive to manufacture.

45 With these and other objects in view, the invention consists in the features of construction, combination and arrangement of parts, as will be hereinafter more fully described, illustrated in the accompanying

drawing disclosing the preferred embodiment of the invention and pointed out in the claims hereunto appended.

In the accompanying drawing.

Figure 1 is a fragmentary sectional elevation through an internal combustion engine 55 showing in elevation its valve, valve spring and rest for the latter, with the tool constructed in accordance with the invention applied.

Figure 2 is a bottom plan view of the 60 tool alone.

Figure 3 is a detailed elevation of the adjustable valve engaging element of the tool.

Figure 4 is a side elevation thereof, the same being partly in section and in engaging 65 relation to a slotted valve head.

Figure 5 is a sectional view on the line 5-5 of Figure 1 looking in the direction of the arrows.

Figure 6 is a fragmentary detail view of 70 the hand grip for the links forming the break joint between arm and lever of the device.

Similar reference characters indicate corresponding parts throughout the several 75 views in the drawing.

Referring to the drawing in detail, A designates generally a portion of an internal combustion engine block, B the valve mounted in the usual or customary manner within the block, C the valve spring of conventional type and D the removable spring seat, which is held upon the stem of the valve B by a removable cross pin engaged in said stem of the valve B in the usual well known 80 manner.

The tool constituting the invention comprises a lever 10 which is preferably elongated and is formed with a handle terminal 11, the said lever being deformed intermediate its ends to provide an acute angular end portion 12 remote from the handle terminal 11 thereof. This acute angular end portion 12 is longitudinally slotted transversely thereof for a distance to provide opposed resilient jaw extensions 13 which diverge outwardly from each other and are bent laterally outwardly to provide offset 95

terminals 14 having inwardly directed jaws or claws 15. Slidably embracing the resili-
ent extensions 13 is a ring 16 which when
moved will compress said extensions 13 or
5 permit the same to expand outwardly away
from each other, so that in this manner the
claws or jaws 15 can be brought into positive
engagement with the spring rest D, accord-
ing to the size of the same as is clearly illus-
trated in Figure 1 of the drawing.

Carried by the acute angularly disposed end portion 12 of the lever is a substantially goose-neck shaped arm 17, which is swingingly connected to said lever through the medium of the pivot 18. This arm 17 at its free end is formed with an internally threaded eye 19 in which is engaged an adjusting screw 20 having at its outer end a cross head 21, while the inner end is furcated medially for removably receiving a reversible keeper 22, the same being held fast through the medium of a coupling screw 23 engaged in said screw 20 and keeper 22 as is clearly illustrated in Figures 3 and 4 of the drawing.

25 To make clear the utility of the reversible keeper, it will be pointed out that standard valve heads appear to be of two kinds, one being formed with a groove in and across the outer face of the valve head for the engagement of a screw driver therewith and the other valve head is devoid of the groove but in lieu thereof has formed in the outer face a pair of spaced holes so as to permit a double lug tool to be engaged therewith. To render the lifter universal for these types of valve heads, it is constructed for use with a reversible keeper 22. This reversible keeper at one end is formed with spaced lugs 24 adaptable for engagement in suitable holes formed in the valve head 25 of the valve B as illustrated in Figure 1 of the drawing, which valve head is one conventional type. The keeper 22 at its other end is formed with a screw driver like end 26 which is adaptable for engagement in a slot 27 in the valve head 28 shown in Figure 4 of the drawing, this head being another conventional type.

Connected with the lever 10 and arm 17 is
50 a break joint brace, including the links 29
and 30, respectively, these being swingingly
connected by pivots 31 to the lever and arm,
respectively, as shown in Figure 1 of the
drawing. The link 29 is of the slotted type
55 and has pivoted therein at 32 the said link
30 so that both links 29 and 30 have knife
like opening and closing action and when
the links are opened in alignment with each
other the said link 30 will abut the back of
60 the link 29 to sustain the brace in extended
position to lock the lever 10 and arm 17 in
fixed relation to each other, when the tool is
applied and engaging the valve B and
spring rest D for sustaining the spring C
65 compressed to permit the free and easy re-

removal of the cross pin *a* from the stem of the valve B as is disclosed in Figure 1 of the drawing.

The pivot 30 has formed thereon a cross head hand grip 33, which permits the user of the tool to readily break the brace, so that the lever 10 can be swung relative to the arm 17 of the tool as will be clearly obvious. 70

In the operation of the tool the brace is 75
broken at the pivot 32 so that the claws or
jaws 15 can be brought into engagement
with the spring rest D and thereafter the
arm 17 moved to overhang the valve B,
whereupon the keeper 22 is engaged with the 80
valve head of said valve B and the handle
terminal 11 is moved in a direction to cause
the spring C to compress and when in com-
pressed position the brace is extended so
that the links 29 and 30 are in alignment 85
with each other, thereby holding the tool
locked in applied position as illustrated in
Figure 1 of the drawing. 1 5

To release the tool it is only necessary for the operator to engage the grip 33 and break the brace outwardly, whereupon the tool can be manipulated for its removal from engagement with the valve and the spring rest as will be apparent. The crossed relation of the grip 33, with respect to the links 29 and 30, will prevent the fingers of an operator from becoming pinched, when said links are broken, and the lever 10 closely approaches the arm 17, as this grip 33, prevents these parts from coming together.

What is claimed is:

1. In a tool of the character described, an operating lever having a split shank providing oppositely arranged forwardly divergent resilient extensions, there being offset claws formed at the extremities of said extensions, means for compressing the extensions and embracing the same, a substantially goose-neck shaped arm pivotally mounted on the lever intermediate its ends, an adjusting screw carried by the arm, a reversible keeper fitted in the screw and adapted to engage a valve head, and means for locking the arm and lever in fixed relation to each other. 110 115

2. In a tool of the character described, an operating lever having a split shank providing oppositely arranged forwardly divergent resilient extensions, there being offset claws formed at the extremities of said extensions, means for compressing the extensions and embracing the same, a substantially goose-neck shaped arm pivotally mounted on the lever intermediate its ends, an adjusting screw carried by the arm, a reversible keeper fitted in the screw and adapted to engage a valve head, and a break joint brace pivotally connected to the lever and arm. 120 125

C 3. In a tool of the character described, an operating lever having a split shank providing

ing oppositely arranged forwardly divergent resilient extensions, there being offset claws formed at the extremities of said extensions, means for compressing the extensions and embracing the same, a substantially goose-neck shaped arm pivotally mounted on the lever intermediate its ends, an adjusting screw carried by the arm, a reversible

keeper fitted in the screw and adapted to engage a valve head, a break joint brace ¹⁰ pivotally connected to the lever and arm, and a grip formed on one of the parts of said brace.

In testimony whereof, I affix my signature hereto.

PERRY OTIS WISWELL.
